UNITED STATES PATENT OFFICE.

JOSEPH F. MILLIGAN, OF CHEYENNE, WYOMING.

SYRINGE.

984,148.

Specification of Letters Patent. Patented Feb. 14, 1911.

Application filed January 25, 1910. Serial No. 539,950.

To all whom it may concern:

Be it known that I, JOSEPH F. MILLIGAN, a citizen of the United States, residing at Cheyenne, in the county of Laramie and 5 State of Wyoming, have invented certain new and useful Improvements in Syringes; and I do hereby declare the following to be a full, clear, and exact description of the invention, such as will enable others skilled 10 in the art to which it appertains to make and use the same.

My invention relates to new and useful improvements in syringe constructions and my object is to provide means for attaching 15 a nozzle to a flexible bag or body portion.

A further object is to provide a valve within the neck of the bag to regulate the flow of the contents from the bag.

20 A further object is to provide a casing for the bag, whereby the same will be protected.

A further object is to provide movable side walls in the casing, whereby pressure 25 may be applied to the bag to force the contents thereof through the nozzle.

A further object is to provide means to normally retain said movable side walls out of direct contact with the bag, and, a further 30 object is to provide suitable tablet receiving receptacles on the walls of the casing.

Other objects and advantages will be hereinafter described and more particularly pointed out in the specification and claims.

35 In the accompanying drawings which are made a part of this application, Figure 1 is a side elevation of the syringe complete. Fig. 2 is a vertical central sectional view therethrough, and, Fig. 3 is a transverse 40 sectional view thereof.

Referring to the drawings in which similar reference numerals designate corresponding parts throughout the several views, 1 indicates the body of my improved syringe, 45 which is preferably constructed of flexible rubber, the upper end of said body being connected to a neck 2, which may be constructed of metal or other suitable material, such as hard rubber or the like.

50 Attached to the upper end of the neck 2 is a nozzle 3, which is constructed in the usual manner and is threaded on to the neck 2, a portion of the exterior surface of said nozzle being threaded to receive the 55 threads of a cap 4, which cap is adapted to fit over the opening in the end of the

nozzle to prevent leakage when the syringe is being transported or is not in use.

Surrounding the body portion 1 and attached in any suitable manner to the lower 60 end of the neck portion 2, is a casing 5, which casing is preferably constructed of metal so as to thoroughly protect the body, portions of the side walls 6 being movable, whereby pressure may be applied to the 65 body 1 to expel the contents thereof through the nozzle. The movable side walls are slidably mounted at their corners on rods 7, which rods are carried by the solid portion of the casing and in order to normally hold 70 the movable side walls out of engagement with the body 1, springs 8 are placed around said rods, the ends of the springs engaging the movable side walls.

In order to properly apply pressure to 75 the movable side walls, they are each provided adjacent their longitudinal centers with a boss or circular rib 9, thereby providing seats into which the ends of the thumb and finger may be placed when applying inward pressure on the movable side walls and as said bosses are placed at the centers of the side walls, the pressure thereon will be equal throughout the length of said side walls. To prevent the flow of the contents of the 80 body into the nozzle 3, as when the syringe is being transported or tilted to apply the same to use, the upper end of the neck 2 is provided with a closure 10, which is preferably formed integral with the neck, said 85 closure having suitable ports 11 through which the contents of the body may flow and over said ports is disposed a valve 12, said valve when seated over the ports, closing the same and preventing the discharge 90 of the contents of the body.

The valve 12 is provided with a depending stem 13, the lower end of which is extended through a guide 14, the lower end of the stem having a head 15 thereon between which and 100 the guide 14 is placed a spring 16, said spring being spiral and extended around the stem, the tension of the spring being employed to normally hold the valve seated over the ports in the closure.

Secured to or formed integral with the edge walls of the casing 1 are tubes 17, into which is to be placed tablets or the like of medicine, which tablets are to be used in connection with the contents of the body 1 110 for treating diseases for which the syringe is particularly designed.

The liquids are entered into the body 1 through a port 18 formed in the neck portion 2, said port being normally closed by any suitable form of stopper or cap 19 and by this means it will be readily seen that the body can be quickly filled when desired.

It will thus be seen that I have provided a very convenient form of syringe for containing liquid and solid medicines and one 10 that can be readily carried in the pocket and by providing the caps and valve, as shown, any leakage of the liquid within the syringe will be prevented. It will further be seen that the device can be cheaply, as 15 well as strongly and durably, constructed and instead of making the casing of metal, the same can be formed of hard rubber if preferred. It will likewise be seen that a greater or less quantity of the liquid may be 20 expelled from the body by increasing or decreasing the pressure on the side walls of the syringe, which is a valuable feature over the other forms of syringe in which it is necessary to refill the same to obtain an additional amount of liquid.

What I claim is:

1. In a syringe, the combination with a flexible body and a nozzle attached thereto; of a casing surrounding said body having 30 the side walls thereof formed in sections, one section of each wall adapted to be manually depressed to force the contents of the body through said nozzle and spring means to normally retain the movable sections out of contact with said body.

2. A syringe, comprising the combination with a flexible body, a neck carried by said body and a nozzle attached to said neck; of a casing surrounding said body, the side

walls of said casing being movable, rods 40 upon which the side walls are mounted, and springs surrounding said rods and exerting outward pressure on the movable side walls, whereby the side walls will be normally held out of contact with the body. 45

3. A syringe, comprising the combination with a flexible body, a neck carried by said body and a nozzle attached thereto; of a casing surrounding said body having the side walls thereof formed in sections, one 50 section of each wall being adapted to be depressed, rods upon which the movable sections are mounted, springs encompassing said rods and normally retaining said last referred to sections out of contact with said 55 body, and means carried by said neck to retain the contents of said body until forced outwardly by the depression of said movable sections.

4. In a syringe, the combination with a 60 flexible body member having a nozzle attached thereto; of a casing surrounding said body having portions of the side walls thereof of movable, means to normally retain said movable portions out of contact with said 65 body, and additional means to normally retain the contents in said body until forced outwardly by the depression of said movable side walls.

In testimony whereof I have signed my 70 name to this specification in the presence of subscribing witnesses.

JOSEPH F. MILLIGAN.
